[57] ABSTRACT

A magnetic fax system is disclosed. The system is adapted to receive information from a record medium

and from a remote station, as well as to transmit information. When a record medium is provided, a magnetizing bar is used for magnetizing signals on the record medium. An endless travelling transfer magnetic sheet is provided for receiving the first magnetic signals from the record medium after they have been magnetized. A pair of coating rollers press the endless transfer magnetic sheet to the record medium and an AC field is simultaneously supplied for transferring the magnetic signals to the endless magnetic sheet. A scanning device is provided downstream along the path of the endless magnetic sheet from the magnetizing region and by means of this device magnetic signals transmitted from a remote location may be transferred to the endless magnetic sheet and signals may be transmitted from the endless magnetic sheet to a remote location. The scanning device includes a recording head and a magnetic reading head which are positioned adjacent the endless sheet. An induction coil is coupled to the magnetic reading head and the recording head for transferring signals from the endless magnetic sheet and for transferring signals to the magnetic sheet. The endless sheet passes between a second set of coating rollers which are located downstream from the scanning device, one roller extending into a supply of magnetic powder which has a resin coating thereon and the powder is thereby transferred to the endless sheet. The endless sheet next passes to a printing region which includes a third set of coating rollers through which the endless sheet and a recording paper are simultaneously passed, the resin being thus transferred to the recording paper. A heating plate is positioned for melting the resin coating of the magnetic powder which has been transferred onto the recording paper. A demagnetizing system, such as a permanent magnet, is positioned along the path of the endless sheet for erasing the magnetic image.

MAGNETIC FACSIMILE AND READ-OUT DEVICE FOR ORIGINAL

BACKGROUND OF THE INVENTION

The present invention relates to a magnetic fax, i.e., a magnetic facsimile which electromagnetically converts data stored on a magnetic recording medium into electric signals and transmits the derived electric signals, and which also converts received electric signals into magnetic characters and reproduces the magnetic characters onto a magnetic recording medium.

In the known facsimile systems information such as characters, numerals or symbols recorded on an original has photoelectrically been converted into electrical signals, so that the construction of the device is complicated.

SUMMARY OF THE INVENTION

The present invention has for its object to provide a new type of magnetic fax which is easily operated and has a simple construction.

The present invention has for its further object to provide a magnetic fax in which, during transmitting and receiving as well as when preserving information on the magnetic recording medium, the contents of the information can keep secret and in which preservation and multiprinting of the magnetic latent image at the time of transmitting or receiving the signals is possible, and the characteristics of the magnetic transfer system without a dark room can fully be utilized.

According to the invention, a magnetic fax comprising means for receiving a record medium where magnetic signals such as magnetic characters are recorded, a magnetizing means for magnetizing the signal recorded on the record medium, an endless transfer magnetic sheet for the magnetic signal magnetized by the magnetizing means, a pressing means for pressing the magnetic signal after it has been transferred to the transfer magnetic sheet, a supplying means an AC transfer magnetic field for transferring the magnetic signal to the transfer magnetic sheet by pressing the magnetic signal to the transfer magnetic sheet by means of the pressing means, one or more magnetic heads for reading out a magnetic latent image transferred to said transfer magnetic sheet, a transmission and reception scanning means provided with one or more recording heads for recording the magnetic signal on the transfer magnetic sheet according to the receiving signal from outside, an induction coil means for performing transmission and reception of the signal between a transmitting section for transmitting the signal read out by the magnetic head of said scanning means and a receiving section for receiving the signal transmitted from the outside and the recording head for recording the magnetic signal according to the received signal to the transfer magnetic sheet, a developing means for developing the magnetic latent image recorded on the transfer magnetic sheet by the recording head of said scanning means with the use of a magnetic powder, a printing means consisting of a pressing means for pressing a magnetic image developed on the transfer magnetic sheet by the developing means to a recording paper and a fixing means for fixing the magnetic powder transferred by pressing said magnetic image to the recording paper by means of the pressing

means, and a demagnetizing means for erasing the magnetic latent image of the transfer magnetic sheet.

A read-out device for use in the magnetic fax includes means for transferring magnetic signals, such as magnetic characters recorded on an original, to a magnetic sheet, means for adhering magnetic powder for developing a magnetic latent image transferred to the magnetic sheet, and means for transferring a magnetic image developed by the magnetic powder on the magnetic sheet to a recording paper.

BRIEF DESCRIPTION OF THE DRAWINGS

The specific nature of the present invention and advantages thereof will become clearly evident from the following detailed description of a typical embodiment taken in conjunction with the accompanying drawings in which:

FIG. 1 is a perspective view showing an embodiment of a magnetic fax according to the present invention;

FIG. 2 is a plane view showing a scanning section in the embodiment of FIG. 1;

FIGS. 3a, 3b and 3e to 3j are constructional views showing embodiments of the magnetic heads used in the scanning section;

FIG. 3c is an enlarged cross-sectional view of a magnetic wire used in the magnetic head;

FIG. 3d is an enlarged cross-sectional view of a magnetic member used in the magnetic head;

FIG. 4a is a sectional view taken along the line A—A in FIG. 2;

FIG. 4b is a sectional view taken along the line B—B in FIG. 2; and

FIG. 5 is a constructional view of a recording head used in the scanning section.

DESCRIPTION OF PREFERRED EMBODIMENTS

Referring now to FIG. 1, the reference numeral 1 indicates a recording medium having magnetic signals recorded thereon. This information may be deemed the "original." For example, the medium may be a recording paper, a recording card, a recording tape, etc., having magnetic characters printed thereon with magnetic ink. The coercive force H_c of the magnetic signals on the original should be several times larger than the coercive force H_c of a transfer magnetic sheet which is used for receiving a magnetic latent image developed from the magnetic signals of the original 1.

The original 1 is inserted into a receiving section 2 in the direction of an arrow A, and passes through a magnetizing section 3. The original passes between rollers 4 and 9 which define a pressing means for pressing the recording surface of the original 1 against a transfer surface of an endless transfer magnetic sheet 8 extending between rollers 4, 5 and 6. The sheet 8 always travels in the direction shown by arrow 7 by means of the driving roller 4. The original is thereafter removed through a chute 10 in the direction of arrow B.

The magnetizing section 3 for magnetizing the original 1 extends along the entire width of the original 1 in order to magnetize all the magnetic signals recorded across the width of the original 1. However, it is not necessary to construct the magnetizing section 3 as described above if the magnetizing section 3 is movable in the widthwise direction as the original 1 passes.

The magnetizing section 3 can be composed of a DC magnetic field, such as a permanent magnet or an electromagnet, or an AC field such as created by a field

generating mechanism, a pulse magnetic field, etc. In case the permanent magnet is used, the magnetizing section 3 may have a single body having a length sufficient for positioning the member across the width of the original 1 or an assembly of a desired number of permanent magnets each having N and S magnetic fields, and having a desired shape. Further, the magnetizing section 3 can be also positioned on the lower side of the original 1 or both sides can be energized by means of two sections 3.

The endless transfer magnetic sheet 8 has a magnetic transfer surface of a magnetic material which has a coercive force value H_c that it is smaller than that of the original 1 and the magnetic latent image obtained on the transfer surface from the magnetic signals of the original 1 is not erased by an external magnetic field or the like. Moreover, the transfer magnetic sheet 8 is sufficiently wide to transfer all the magnetic signals recorded in the lateral direction of the original 1. As an example of this endless transfer magnetic sheet 8, mention may be made of known magnetic tapes or Permalloy sheets, etc.

Further, the rollers 4 and 9 which press the original 1 and the transfer magnetic sheet 8 together are designed for surely and closely pressing both the sheets in order to improve transfer efficiency, but a slight elasticity is given to the surfaces of the rollers 4, 9 for preventing any excessive pressure.

When the surface of the original 1 and the magnetic transfer surface of the transfer magnetic sheet 8 are passed through between the rollers 4 and 9 a magnetic latent image can be transferred onto the transfer magnetic sheet 8 corresponding to the magnetic signals of the original 1 which are magnetized by the magnetizing section 3. The transfer is accomplished by means of an AC transfer magnetic field. As illustrated in FIG. 1, a means for applying the AC transfer magnetic field comprises a coil 12 wired within the roller 4. An alternating current is supplied between both terminals 12a and 12b of the coil 12.

The reference numeral 13 indicates a transmission and reception scanning section for reading out the magnetic latent image which have been transferred from the magnetic signals of the original 1 to the transfer magnetic sheet 8 (placed in the transmitting side), and for transmitting the read out signal to a transmitting section 14. The section also records signals received by a receiving section 15 on to the transfer magnetic sheet 8 (placed in the receiving side).

The transmission scanning section will be first explained. In FIG. 2, reference numeral 16 denotes a magnetic head for scanning signals to be transmitted. The magnetic head 16 is positioned on a belt 19 extended between pulleys 17 and 18 for scanning the transfer magnetic sheet 8 which proceeds in the direction of the arrow 7.

The magnetic head 16 has the ability to effectively scan the magnetic signals transferred to said transfer sheet 8. The magnetic head 16 shown in FIGS. 3a and 3b comprises an inductance element consisting of a magnetic wire 103 or a magnetic member 104 (refer to FIGS. 3c and 3d) which consists of a magnetic thin film 102 on a lead wire 100 or a conductor 101 with a coil 105 wound thereon. A resonance circuit is formed by connecting the coil 105 to a capacitor 106 in parallel which causes an alternating current to flow through the magnetic wire 103 or the magnetic member 104 and

which acts as a frequency doubler of said alternating current. The change of the phase of said doubled frequency due to the polarity of the external magnetic field is used to detect the micro magnetic field (refer to Japanese Patent Publication No. 10,031/70). This is known as a yoke-type parametric magnetic head and is characterized in that said magnetic wire 103 or the magnetic member 104 forms a part of the magnetic circuit having a slight gap and said gap is formed as a magnetic detecting head.

That is, in FIGS. 3a and 3b, 107a and 107b are yoke portions, flatly and opposingly arranged as illustrated, provided with a gap G at one end thereof, this portion being a head portion H, and being connected to the magnetic wire 103 or the magnetic member 104 to the other ends of the yoke portions. Moreover, the magnetic wire 103 is bonded to the other ends of the yoke portions 107a and 107b by a bonding agent 108 containing a magnetic powder, but in case of the magnetic member 104, it is possible to integrally form the magnetic member with the yoke portions.

In the magnetic head consisting of the above described construction, by applying an exciting alternating voltage e_f between exciting terminals 109a and 109b, a double frequency oscillating voltage of $e2f$ is generated between output terminals 105a and 105b of the coil 105.

If the head portion H approaches the magnetic signal M on the transfer sheet 8, a magnetic flux ϕ of the signal M, due to very small gap G, enters one of the yoke portions, for example 107a (depending on polarity), travels through the yoke portion 107a, the magnetic wire 103 or the magnetic member 104 of the inductance element and then to the other yoke portion 107b. The signal M completes the path of the flux ϕ . Moreover, if the polarity of the magnetic signal M is reversed, the flux ϕ enters into the head portion H and again returns from the head portion H to the signal M through members 107b $\rightarrow$ 103 or 104 $\rightarrow$ 107a.

When the flux ϕ passes through the magnetic wire 103 or the magnetic member 104 of the inductance element in this process, the phase of the double frequency oscillating voltage $e2f$ is determined by the direction of the flux ϕ , and the magnetic signal M can be read out by discriminating it. If the magnetic signal M passes near the head portion H, both ends of the magnetic wire 103 (or the magnetic member 104 of the inductance element) simultaneously are affected. The gap G can be made small by means of etching or the like, so that almost no leaking flux is existent. Specifically by making the gap G narrower than the width of the magnetic signal M the signal may be detected with high sensitivity. Moreover, because of very small gap G of the head portion H, the magnetic head may read out the magnetic signal with high resolution.

Further, even where the voltage of the oscillation circuit is amplitude modulated by the magnetic signal M, the magnetic head is also effective.

The magnetic sensor shown in FIGS. 3e and 3f shows an embodiment of a differential type magnetic head which is constructed by arranging a magnetic wire 103' or a magnetic member 104' in parallel to the magnetic wire 103 or the magnetic member 104, respectively, in the above described magnetic head. This sensor has the advantage eliminating the influence of the external magnetic field as compared with the magnetic head shown in FIGS. 3a and 3b.

FIGS. 3g and 3h show further embodiments wherein, as a part of the magnetic circuit having a slight gap, an orthogonal flux gate which utilizes a magnetic thin film with its rotating magnetization mechanism instead of the double-frequency oscillating circuit described in the above examples. The gap is formed as a magnetic detecting head.

In this case, if an alternating exciting current having an optional waveform such as an intermittent or continuous waveform is applied between the exciting terminals 109a and 109b of the magnetic wire 103 or the magnetic member 104, the phase of the double-frequency component of the output voltage observed at the output terminals 105a and 105b of the coil 105 is either 0 phase or π phase according to the polarity of the flux generated from the magnetic signal M. Here, by using discriminating means, for example by discriminating the phase of the component with the use of a reference phase generating circuit and a synchronous rectifying circuit, the magnetic signal M can be read out, by observing the magnetizing direction and the strength thereof.

Moreover, FIGS. 3i and 3j show differential magnetic heads consisting of an orthogonal flux gate achieved by arranging the magnetic wire 103' and the magnetic member 104' in parallel to the magnetic wire 103 or the magnetic member 104 and winding the coil 105 thereon as illustrated in the figures for removing any influence of the external magnetic field.

In FIG. 3j, 110 shows an electrical insulating material.

Again referring to FIG. 2, the reference numerals 20 to 23 indicate electrically conductive belts extending in parallel to the belt 19 between, respectively, pulleys 26 and 27, 28 and 29, 30 and 31, and 32 and 33. These pulleys are also firmly connected to shafts 24 and 25. The belts 20 and 21 are connected to the exciting terminals 109a and 109b of the magnetic head 16 and the belts 22 and 23 are connected to the output terminals 105a and 105b of the magnetic head 16, respectively.

Further, as shown in FIG. 4(a) each of the main bodies 27a, 29a, 30a and 32a of the pulleys 27, 29, 30 and 32 are made of a non-conductive material, but, on the contact surfaces of the pulleys electrical-conductive rings 34 to 37 are provided so as to non-conductive connect them to the surfaces of the belts 20 to 23. The conductive rings 34 and 35 of the pulleys 27 and 29 are, in turn, connected to terminals 38a and 38b of a primary induction coil 38 wound on the shaft 25, and the conductive rings 36 and 37 of the pulleys 30 and 32 are connected to the terminals 39a and 39b of a primary induction coil 39 wound on the shaft 24, through insulated lead wires 42 and to 43, respectively.

All of the other pulleys 17, 18, 26, 28, 31 and 33 are made of a non-electrical-conductive material.

The reference numerals 45 and 46 show secondary induction coils wound around the outer periphery of the primary coils 39 and 38 at intervals.

In the circuit construction of the above described magnetic head, an alternating exciting current is supplied between terminals 46a and 46b of the secondary induction coil 46, whereby the alternating exciting current can be supplied between the exciting terminals 109a and 109b of the magnetic wire 103 or the magnetic member 104 of the magnetic head 16 through the magnetic induction between the primary and the sec-

ondary induction coils, lead wires 40 and 41, the contact surfaces of the electrical-conductive rings 34 and 35 and the belts 20 and 21. The magnetic head 16 is, in this manner, operated.

Moreover, an output signal between the output terminals 105a and 105b of the magnetic sensor 16 appears at terminals 45a and 45b of the secondary induction coil 45 through the induction action between the primary induction coil 39 and the secondary induction coil 45 which are connected through the contact surfaces of the electrical conductive rings 36 and 37 as an electrical-conductive portion of the pulleys 30 and 32 and the belts 22 and 23 and the lead wires 42 and 43, whereby the desired transmission scanning can effectively be carried out.

The transmission scanning by means of the magnetic head 16 can be carried out by operating the belt 19, and the other belts 20 to 23 are also activated simultaneously with the belt 19 as illustrated.

The reference numerals 47 and 48 indicate shield plates made of ferrite or the like and interposed between the pulleys 28 and 30 and 29 and 31; 49 is a shield plate interposed between the belts 21 and 22. These shield plates 47 to 49 isolate the adjacent belts from magnetic induction which would otherwise be generated between the adjacent belts 21 and 22.

The reference numerals 50 and 51 denote ferrite base layers covered around the outer peripheries of the shafts 24 and 25. These layers are interposed between the primary induction coils 38 and 39 and the shafts 24 and 25, whereby supply and reception of a low frequency alternating current on the order of 10-50 hz., can positively be carried out by the magnetic induction of the alternating current between the primary and secondary induction coils 38 and 46 or 39 and 45.

Next, the reception scanning section will be explained with reference to FIG. 2. The reference numeral 55 shows a recording head for reception scanning, which is a known inductive head made by winding a coil 57 around a magnetic core 56 and forming a head portion H at the open end gap G of the core 56 as shown in FIG. 5. This recording head 55 is provided on a belt 60 which extends between the pulleys 58 and 59, and travels with the belt 60, so as to receive the signal received at the receiving section 15 and transfer the signal onto the transfer magnetic sheet 8 advancing in the direction of the arrow 7.

Further, this recording head 55 is not limited to the construction illustrated in the figure, it is possible to use any type of recording head so long as the received signal may be effectively scanned and received.

The reference numerals 61 and 62 show electrical-conductive belts extending between pulleys 63 and 64 and 65 and 66, respectively, which are firmly connected to the shafts 24 and 25. These belts, 61 and 62, are connected to the terminals 57a and 57b of the coil 57 of the head 55, respectively.

Further, each of the main bodies 64a and 66a of the pulleys 64 and 66 are made of a non-electrical-conductive material, but electrical-conductive rings 69 and 70 are provided on the contact surfaces of the pulleys associated with belts 61 and 62 to form electrical-conductive portions, so as to electrically connect the rings and the belts at the contact surfaces of the belts 61 and 62 and the electrical-conductive rings 69 and 70 of the pulleys 64 and 66. The electrical-conductive rings 69 and 70 are connected to terminals 71a and 71b

of a primary induction coil 71 which is wound around the shaft 25 through insulated lead wires 72 and 73, respectively.

Each of the other pulleys 58, 59, 63, and 65 is made of a non-electrical-conductive material.

The member 74 is a secondary induction coil wound around the outer periphery of the primary induction coil 71 at intervals.

Then, the received signal is supplied between both terminals 74a and 74b of the secondary induction coil 74, whereby the received signal can be supplied between the terminals 57a and 57b of the coil 57 of the recording head 55 through the magnetic induction between the primary and the secondary induction coils, lead wires 72 and 73, the contact surfaces of the electrical-conductive rings 69 and 70 and the belts 61 and 62.

Accordingly, the magnetic signal, such as magnetic characters, based on the signal received from the receiving section 15 by means of the recording head 55 can effectively be received and scanned.

The members 97 to 99 are shield plates interposed between the pulleys 32-58 and 33-59 and between belts 23 and 60, and its effect is similar to that of the above described shield plates 47 to 49.

In the above embodiment a plurality of magnetic heads and recording heads can be provided and appropriately arranged. In such a case, the scanning can quickly be made.

Although in the above embodiment, the use of a plurality of belts in parallel between the pulleys is disclosed, but the subject invention can be also carried out by extending only one wide belt between the pulleys, providing a plurality of track-like electrical-conductive strip along the longitudinal direction thereof, and connecting the strips to the electrical-conductive portions of each pulley.

Further, each belt in the above embodiment is made of an electrical-conductive material and the belt itself serves as an electrical-conductive portion as shown in the embodiment, but each belt can be made of a non-electrical conductive material and an electrical-conductive material could be coated thereon in the longitudinal direction to form an electrical-conductive portion. Moreover, for driving each belt, either one of the shafts is coupled with a driving mechanism and rotated thereby. This driving mechanism is not illustrated in the drawing in detail, but any of known driving mechanisms can be used.

As described above, the transmission and reception scanning sections described in accordance with FIGS. 2 to 6 are embodiments of a belt scanning system, but any other scanning systems such as drum scanning system, etc., can be used. Particularly, in the known scanning system, the supply of the desired electric powder for scanning the magnetic head in the transmission scanning section or supply and reception of the signal in case of transmitting the scanning signal to the transmission section or transmitting the received signal to the recording head from the receiving section during scanning of the recording head in the reception scanning section can be carried out without contact means by use of the magnetic induction in the induction coil section (for example, the primary and secondary induction coils in the above embodiment), so that noise caused during the supply and reception of the signal can be prevented, and the supply and reception of the

signal in such kind of the scanning systems can precisely be achieved.

Moreover, after the data are transferred to the magnetic sheet 8, the magnetic signal of the original 1 is scanned and read out by the magnetic head 16 in the above read out scanning section adjacent the moving sheet 8 and is transmitted to the receiving section through the necessary signal treating circuit and the transmission section 14.

Further, the signal received by the receiving section 15 can be recorded as a magnetic latent image on the transfer magnetic sheet 8 by means of the recording head 55 of the record scanning section through the necessary signal treating circuit.

Thereafter, the transfer magnetic sheet 8 is moved forward and passed through a developing section 78. The developing section 78 comprises a roller 5 and a coacting roller 77. Around the periphery of the roller 77 is adhered magnetic powder 76, which is stored in case 75. The powder is coated with synthetic resin. Therefore, the magnetic latent image on the transfer magnetic sheet 8 can be developed by the magnetic powder 76.

Further, the developing portion 78 can also be constructed to inject the magnetic powder in a certain space so as to prepare an atmosphere of magnetic powder, by spraying the magnetic powder and by means of directly adhering the magnetic powder to the magnetic sheet by a brush or the like. Reference numeral 79 indicates a printing section, which consists of a pressing means for pressing a magnetic image on the transfer magnetic sheet 8 (developed at the developing section --onto recording paper 80, and a fixing means for fixing the transmitted magnetic powder 76 on the recording paper 80. The recording paper 80 of the thus illustrated printing section 79 is passed between a roller 82 which is in contact with a bonding agent 81 and a coacting roller 83, and then passes between rollers 6 and 84 which act as a pressing means for pressing the magnetic image from the transfer magnetic sheet 8 onto the recording paper 80 and is further passed under a heating plate 85 which serves as a fixing means for fixing the magnetic powder transferred to the recording paper 80, and is then pulled in the direction of an arrow C by means of pull rollers 86 and 87 provided in front of the heating plate 85.

Then, after passing through the developing section 78, the portion having the magnetic image of the transfer magnetic sheet 8 is pressed against the recording paper 80 by passing it through the rollers 6 and 84, and the pattern of the magnetic powder 76 as a magnetic image of the magnetic sheet 8 is transferred onto the recording paper 80 since the pressed surface of the recording paper 80 is coated with the bonding agent 81.

The recording paper 80 is removed, and if it is passed under the heating plate 85, the synthetic resin coating of the magnetic powder is heated and melts, whereby the magnetic powder can be fixed on the recording paper 80 as a visible image based on the magnetic image developed on the transfer magnetic sheet 8.

There has been described an embodiment for recording on the recording paper 80, the magnetic signal recorded on the transfer magnetic sheet 8 based on the signal received by the receiving section 15 by means of the record scanning section and in similar manner, the magnetic signal of the original 1 transferred to the

transfer magnetic sheet 8 can be recorded on the recording paper 80.

Further, instead of using the magnetic powder coated with the above described synthetic resin, if recording paper 80 made of waxed paper is used, the magnetic powder transferred to the recording paper 80 is fixed on the recording paper 80 by heated wax, or if a bonding agent containing a thermosetting resin instead of a usual bonding agent is used, if the magnetic powder on the transfer magnetic sheet 8 is transferred to the recording paper 80 and fixed thereon by heating and hardening the thermosetting resin contained in said bonding agent, a mere magnetic powder can be used.

The member 88 is a cleaning section for removing residual sediments of the magnetic powder and the bonding agent, and this cleaning section 88 is so constructed that the transfer magnetic sheet 8 is guided by means of the rollers 89 and 90, and the residual magnetic powder on the transfer magnetic sheet 8 or the bonding agent and other adhesives adhered at the time of transferring the image is removed by a sliding knife 91 at the time the sheet passes the roller 89.

The member 92 is a demagnetizing section for erasing the magnetic latent image of the transfer magnetic sheet 8 and this demagnetizing section 92 has a construction similar to the magnetizing section 3.

When the magnetic latent image transferred or recorded on the transfer magnetic sheet 8 is repeatedly recorded on the recording paper, the demagnetizing section should, of course, be constructed so as not to operate during said process. Then, the magnetic latent image on the transfer magnetic sheet 8 can be erased when it passes through the demagnetizing section 92, and the above described process can be repeated as provided for a transfer or recording of a new magnetic latent image.

As apparent from the above explanation, according to the magnetic fax of the present invention, the transmitting original, the transfer magnetic sheet for transferring such original, and the printing the information to the recording paper can all be carried out by magnetic means, and it is possible to scan it magnetically without confirming with the naked eye, so that the present invention is preferable to transmit or receive information from a document which should be kept secret.

Further, the present invention is to magnetizes a magnetic signal such as magnetic characters recorded on the original, presses the original to the transfer magnetic sheet and transfers it onto the transfer magnetic sheet by the alternating magnetic field, and transmits it to the receiving section, or records the information recorded on the original on the recording paper (reading out such that the recorded information which cannot optically be read out is read), so that any irregularity of the magnetic field of the magnetic signal such as magnetic characters recorded on the original is eliminated and the magnetic field of the magnetic signal recorded on the original may be standardized with uniform strength, whereby as compared with the case of the magnetic transmission or recording by means of a direct reading out of the information recorded on the original, the information recorded on the original can precisely and clearly be transmitted or recorded or read out.

The present invention carries out the transmission or reception of the signal by transferring or recording it to the transfer magnetic sheet, so that the quality of the signal is maintained, more particularly, the transfer magnetic sheet is endless, so that the repeating and continuous transmission or receipt of the signal is possible as long as the signal is not erased by the demagnetizing section, while the printing on the recording paper when receiving the signal can be carried out without requiring any dark room, which is necessary for the conventional photoelectric recording, so that the device can be simplified and requisite peripheral equipment is minimized.

The present invention carries out the supply and reception of the signal between the magnetic head and the transmitting section or the recording head and the receiving section in the scanning section by means of the magnetic induction of the induction coil so that the noise can be prevented and precision of the scanning can be improved.

Particularly, according to the invention, the magnetically recorded original is directly read out, so that the magnetically recorded original can easily and promptly be read out while the conventional system requires the magnetic detecting means and hence magnetic recording means, and moreover the document is recorded magnetically and cannot be read out optically or the numerals or symbols such as a deposit account, credit card, etc., can simply be read out.

What is claimed is:

1. A magnetic facsimile, comprising:
means for receiving a record medium, first magnetic signals being previously recorded upon said record medium;
magnetizing means positioned adjacent said receiving means for magnetizing the first magnetic signals on said record medium;
an endless transfer magnetic sheet for receiving the first magnetic signals from said record medium after the magnetization thereof, said sheet being driven in an endless path;
pressing means operatively connected to said endless transfer magnetic sheet and said recording medium for pressing together the magnetized recording medium and said endless magnetic sheet;
means supplying an AC field coupled to said pressing means for transferring the first magnetic signals to the endless magnetic sheet while said endless magnetic sheet and said record medium are being pressed together;
a scanning means positioned downstream along the path of said endless sheet from said pressing means and having at least one recording head for recording a second magnetic signal onto said endless transfer magnetic sheet, said second magnetic signal being received by a receiving means from an outside source, and having at least one magnetic head for reading a magnetic latent image on said endless transfer magnetic sheet for transmitting said signal to an outside station via a transmitting means;
induction coil means coupled to said scanning means for transferring signals from said endless magnetic sheet to the transmission means via said magnetic head and for transferring signals to the receiving means to said endless magnetic sheet via said recording head;

developing means positioned adjacent said endless transfer magnetic sheet downstream from said scanning means for developing the magnetic latent image on said endless sheet by means of a magnetic powder, said powder being coated onto said endless sheet;

printing means positioned along the path of travel of said endless sheet and downstream from the development means for transferring a magnetic image from said endless sheet to a recording paper, said 10

printing means comprised of a pressing means for pressing the magnetic image onto the recording paper by transferring the magnetic powder and a fixing means for fixing the magnetic powder onto the recording paper; and

demagnetizing means positioned along the path of said endless sheet downstream of said printing means for erasing the magnetic image on said transfer magnetic sheet.
